UNITED STATES PATENT OFFICE

CLARENCE W. HEWLETT, OF SCHENECTADY, NEW YORK, ASSIGNOR TO GENERAL ELECTRIC COMPANY, A CORPORATION OF NEW YORK

ELECTRIC SWITCH

Application filed October 26, 1927. Serial No. 228,888.

My invention relates to electric switches and particularly those operated in an insulating liquid. An object of my invention is the provision of an improved switch of this type which is especially adapted for the control of large capacity power circuits and which will successfully interrupt the circuit in a minimum time after the contacts begin to separate.

My invention will be better understood from the following description taken in connection with the accompanying drawing, and its scope will be pointed out in the appended claims.

Referring to the drawing, Fig. 1 is a cross sectional view of a switch in closed circuit position embodying my invention; Fig. 2 is a fragmentary sectional view taken on the line 2—2 of Fig. 1; and Fig. 3 is an elevation of the switch in open circuit position drawn to a reduced scale.

In the drawing the base or frame 1, shown mounted upon the liquid and gas receptacle 2, is provided with a central opening into which is securely fastened the casing 3 of insulating material. Fixed in this casing is the contact 4 secured by the nut 5 and having the terminal 6 and slidably mounted in the casing is the cooperating movable contact rod 7. The rod fits loosely in the casing but passes through a stuffing box 8 fastened into the outer end thereof. On the stuffing box 8 is secured the band 9 to which is fastened the other terminal, not shown. In the closed circuit position of the switch the contact rod 7 is held firmly against the fixed contact 4 by the levers 11 pivotally mounted on the rods 12 and engaged by the coil springs 13.

The contacts are caused to separate and any arc that may be drawn therebetween is extinguished by means of an insulating fluid which for example may be a liquid such as oil. For this purpose I have provided the casing 3 with a transverse passage 15 extending therethrough at right angles to the contact rod 7 and at a point immediately in front of the fixed contact 4. This passage connects with another passage 16, shown somewhat larger, in the frame 1 into which extends the plunger 17 through the stuffing box 18. Rods 20 connected at their upper ends by the plate 21 and

secured at their lower ends to the frame 1 form guides for the weight 22 which in falling strikes the plunger 17. The weight is shown retained in its raised position by the latch 23 adapted to be released by the electromagnet 55

24. At the end of the downward stroke of the plunger the weight and plunger are brought to rest and the shock thereof cushioned by the engagement of the plate 25 on the plunger with the rubber pads 26 on the supports 27. Below the casing 3, the passage 15 continues straight on down through the insulation 30 terminating in a valve seat upon which the valve 31 normally rests. The receptacle 2 encloses the valve 31 and is shown 65 provided with insulation lining 32 to prevent an arc that may be deflected past the valve from reaching the metallic walls. Plate 33 supported through the insulation cylinders 34 from the insulated rods 35 carries 70

the valve and the coil spring 36 by which the valve is closed. Vent opening 38 is provided at the top of the receptacle 2 for the escape of gas and a lower opening 39 serves for the admission or withdrawal of insulating liquid to 75

maintain the desired level thereof in the receptacle.

After each circuit opening operation the weight 22 is raised by hand or suitable means until the latch 23 is engaged. The plunger 80 17 also may be raised by hand or may be raised by pumping the insulating liquid through the pipe 40 past the check valve 41 and into the passage 15. The plunger is shown hollow for lightness and for collecting gas, a valved vent 42 being provided at the upper end of it to permit the escape of any gas that collects therein.

The outward movement of contact rod 7 is checked by the buffer comprising the plate 85 45 supported by the rods 12, the shock being cushioned by the rubber plate 46. Secured to the outer side of the plate 45 is the solenoid 48 which when energized is adapted to drive its plunger 49 inward against 90 the spring 50 to return the rod 7 to such a position that the levers 11 may engage over the end of the rod and complete the inward stroke.

When the switch is to be operated to open 100

the circuit controlled thereby, the weight 22 is released by moving the latch manually or by the solenoid 24 which if desired may be load responsive. The energy acquired by 5 the falling weight is delivered to the plunger which produces a sudden high pressure of the insulating liquid. The contact rod 7 first is driven outward to the limit of its movement, the rod being preferably hollow to 10 lighten it, and immediately after the valve 31 is forced open thus releasing the liquid after the contacts have separated. As a result a stream of cool insulating liquid is forced at a 15 high velocity directly across any arc that is drawn between the contacts. The flow of liquid is through a straight passage where friction and eddy losses are a minimum and the arc and hot gases are carried away from both contacts, thereby avoiding all possible 20 burning thereof. These features, together with the advantage of the high speed of the initial separation of the contacts, result in the complete interruption of the circuit in less than one half cycle of a sixty cycle circuit. 25

I have chosen the particular embodiment described above as illustrative of my invention and it will be apparent that various modifications may be made without departing 30 from the spirit and scope of my invention which modifications I aim to cover by the appended claims.

What I claim as new and desire to secure by Letters Patent of the United States is:

- 35 1. An electric switch comprising relatively movable contacts, means for subjecting the contacts to a sudden pressure of insulating fluid to cause separation thereof, means providing a path of escape for the fluid passing 40 between the contacts extending transversely to the direction of relative movement thereof, and valve means controlling said path constructed to open in response to a predetermined pressure of the fluid.
- 45 2. An electric switch of the liquid break type comprising a pair of relatively movable contacts, a casing in which said contacts are mounted having a passage for insulating liquid extending transversely through the 50 path of relative movement of the contacts, means for producing a sudden pressure of said liquid to separate the contacts and yielding means for normally closing said passage.
- 55 3. An electric switch of the liquid break type comprising a pair of cooperating contacts, a casing in which said contacts are mounted for relative movement, said casing having a passage containing insulating liquid extending at right angles through the 60 path of relative movement of the contacts, means for producing a sudden pressure of liquid in the passage at one side of the contacts and a yieldingly closed valve controlling the escape of liquid from the passage at the 65 other side of the contacts.

4. An electric switch of the liquid break type comprising an insulating casing, a contact mounted therein, a cooperating movable contact mounted therein for movement longitudinally out of engagement with the other contact, said casing having a transverse passage containing insulating liquid extending in opposite directions from said contacts, means for exerting pressure on the liquid at one side of the contacts, a receptacle at the other side thereof and a spring pressed valve controlling the flow of liquid from the passage to the receptacle. 70 75

5. An electric switch of the liquid break type comprising an insulating casing, a fixed contact mounted therein, a cooperating contact rod mounted to slide longitudinally therein, said casing having a straight transverse passage containing insulating liquid and arranged to intersect an arc drawn between the contacts, means comprising a plunger for producing a sudden pressure of liquid at one end of said passage adapted to separate the contacts and a spring closed valve at the other end of the passage adapted 80 to release the liquid after the contacts have separated. 90

6. An electric switch comprising relatively movable cooperating contacts, means for subjecting the contacts to fluid pressure to 95 cause a rapid separation thereof, means forming a path of escape for the fluid from the contacts and means for preventing the escape of fluid until the pressure thereof reaches a predetermined value. 100

7. An electric switch comprising relatively movable cooperating contacts, a contact supporting member in which one of said contacts is mounted to move longitudinally, said member having a transverse passage 105 therethrough containing insulating liquid and arranged adjacent the point of separation of the contacts, means for producing a pressure of the liquid at one side of the contacts and means for preventing the escape 110 of the liquid from the opposite side of the contacts until a predetermined pressure has been reached.

8. An electric switch comprising an insulating casing having a bore, a fixed contact mounted in said casing, a contact rod fitting said bore and adapted to be separated from the fixed contact, said casing having a transverse passage containing insulating liquid adjacent the point of separation of 115 said contacts, a spring closed valve closing one end of said passage and means for producing a sudden pressure of liquid at the other end of said passage. 120

In witness whereof, I have hereunto set my hand this 25th day of October, 1927.

CLARENCE W. HEWLETT.
